UNITED STATES PATENT OFFICE.

FRANK HINDE AND WALTER H. FLEWELL, OF EARLY, IOWA, ASSIGNEES OF ONE-THIRD
TO SCOTT RUTLEDGE, OF EARLY, IOWA.

AUXILIARY COOLING SYSTEM FOR INTERNAL-COMBUSTION ENGINES.

1,299,467.

Specification of Letters Patent.

Patented Apr. 8, 1919.

Application filed February 15, 1918. Serial No. 217,366.

To all whom it may concern:

Be it known that we, FRANK HINDE and WALTER H. FLEWELL, citizens of the United States, residing at Early, in the county of Sac and State of Iowa, have invented certain new and useful Improvements in Auxiliary Cooling Systems for Internal-Combustion Engines, of which the following is a specification.

10 The invention has for an object to enable the incorporation upon internal combustion engines of motor vehicles such as are in familiar use, an auxiliary water circulation system having a limited amount of radiation, whereby the engine may be maintained at a higher temperature than is possible with the ordinary radiator, being specially intended for use in extremely cold weather. It is an important aim of the invention to 15 enable the incorporation of this auxiliary device without the removal of the ordinary radiator usually mounted upon the front of the vehicle. An additional purpose is to so construct the appliance that it may be 20 readily incorporated upon a vehicle within the hood ordinarily employed to inclose the engine. Another important aim is to improve the structural features of the device, particularly with reference to the connections 25 between a water tank element and the water connections of the motor.

30 Additional objects, advantages and features of invention reside in the construction, arrangement and combination of parts as hereinafter described and shown in the drawings, wherein,

Figure 1 is a front elevational view of one of the possible embodiments of our invention,

40 Fig. 2 is a side elevation thereof.

Fig. 3 is a side elevation of an engine equipped with a modified form of support for the coil, while,

Figs. 4 to 6 illustrate plan views of blanks 45 of mounting devices.

There is illustrated a motor 10 of a familiar construction, having a water jacket portion 11, the upper part of which is included in a cylinder head casting 12, secured by the usual cap screws 13, suitably located. The water jacket is formed with an inlet 14 at its lower part, and an outlet 15 at its upper forward end, the inlet being located centrally of the motor at one side. 50 An ordinary water radiator 16 is shown in

front of the engine, in its usual relation to the engine. Mounted over the engine there is a reservoir 17, the reservoir being suitably shaped at its upper side to avoid abrasion or obstruction of the hood 18, and being 60 carried upon resilient brackets 19 secured upon the upper side of the engine by certain of the cap screws by which the head casting 11 is held upon the cylinder casting of the motor. The brackets 19 are located 65 one adjacent the forward end of the reservoir, and one adjacent the rear end, and each is formed integrally of one bar of resilient metal of suitable strength having an upper horizontal portion 20, one end portion being 70 bent downwardly at right angles thereto, as at 21, and having a horizontal foot flange 22 formed at its extremity to rest snugly upon the upper side of the head 12. The opposite end portion of the bracket is bent 75 inwardly beneath the horizontal portion 20, so as to lie snugly thereunder, and curved downwardly in the form of an ogee, whereby its extremity may rest upon the top of the head 12, this end portion being located beneath the portion 20 intermediately of the length of the latter, so that the bracket may be projected considerably beyond one side of the motor, as will be readily understood. 80 The foot flange 22 is disposed upon the left side of the head 12 while the opposite end portion 23, is adapted to be adjusted upon the top of the engine at the right hand side, or on the side opposite that at which the spark plugs are usually located, which in 85 some cases may be the left side, and it will be readily understood that the brackets may be reversed in such cases. The reservoir 17 is disposed upon the horizontal portions 90 of the bracket, and is of a width less than 95 the length of the portion 20, which extends transversely of the motor. Engaged over the receptacle and against each side, there is a strap yoke 25 alined with each bracket, its extremities being shaped into screw elements 26, which are extended through suitable apertures in the portion 20 and the in-turned part of the bracket thereadjacent, nuts 27 being engaged therewith to clamp 100 the reservoir upon the brackets.

The reservoir is provided with a filler spout 28, having a filler cap 29 of a familiar form, and is provided with an inlet nipple 30 at its forward end, extending horizontally, while at the rear end upon the bottom 110

- of the reservoir an outlet nipple 31 is located having a form and direction to be subsequently indicated. The cylinder head 12 is formed with an outlet connection 15, and 5 a U fitting 33 is provided, having a base flange 34 which may be bolted to the flange 35 of the outlet 15, the opposite end of the fitting extending in alinement with the inlet 30 of the reservoir, so that a hose connection 10 32 may be readily formed in the familiar way. A bracket piece 40 is secured by the bolts 41 holding the fitting 33, this bracket piece extending laterally beside the engine, and being turned forwardly in a vertical 15 plane beside the engine. The forwardly extended part of the bracket is apertured and receives a bolt 41' therethrough by which a mounting lug 42 of a cooling coil 43 is secured, the lug 42 being formed from a 20 blank of sheet metal of suitable thickness, provided with lateral arms 44 which are bent outwardly to receive parts of the coil therebetween, and are then bent inwardly around respective reaches of the coil, whereby the 25 latter is secured. The coil 43 in the present instance is in substantially the form of the letter W, with the side strokes terminating toward the rear of the motor, and the A shaped central portion stopping short of 30 the outlet connection 14 of the motor. The lower arm of the coil, 45, is bowed downwardly and provided with a drain cock 46' at its lowest point. The uppermost arm 46 of the coil is considerably longer than the 35 arm 45, and the extremities of both of the last mentioned two arms are extended upwardly in an arc concentric with the bolt 41, for purposes to be described. The outlet nipple 31 of the reservoir 17 is extended in 40 a corresponding arc, in alinement with the terminal of the arc 46 of the coil, while the outlet fitting 47 on the motor has a nipple extension similarly concentric and alined with the terminal of the arm 45 of the coil. 45 Hose section couplings 48 and 49 respectively are engaged between the terminals of the arm 45 and the outlet fitting 47 and the outlet 31 of the reservoir.
- In the use of this appliance, it will be 50 come necessary from time to time to disconnect the coil, and it will be seen that by the relation of the terminals of the arms 45 and 46 to the axes of the bolt 41, connection and disconnection of the hose couplings 48 and 49 is greatly facilitated, as one movement of the coil on the bolt 41 as the pivot serves 55 to move the coil terminals in the proper direction for engagement with the hose, and to permit proper adjustment of the hose couplings thereon and on the outlet nipple. The coupling 48 being first engaged, under upward movement of the coil as described, the terminal of the arm 45 will have some distance yet to move before the hose coupling 49 requires to be adjusted on the outlet 60 nipple 31 and the coil terminal, permitting this to be done after the first coupling has been partly made so that continued pivotal movement of the coil will assure proper engagement of the first hose without further 65 attention. 70
- The bracket elements 21 are of such construction that the reservoir 17 is resiliently supported and its attachment and removal greatly facilitated. 75
- In case it becomes necessary to remove the cylinder head 12, the coil 43 is first disconnected, by loosening the bolt 41 and the hose coupling devices after which the terminals of the arms 45 and 46 may be simultaneously borne downwardly as before explained. The coupling 34 is then loosened and the strap yokes 25 removed from engagement with the brackets 19, which permits removal of the reservoir 17. The cylinder 80 head may then be removed in the usual way, with the bracket 40 and coil attached thereto, if desired, or the coil may be removed by the removal of the bolt 41. The removal of the usual bolts holding the cylinder head 85 will release the brackets 19, which may be readily returned to their proper positions when the parts are again assembled. 90
- If preferred, the coil 43 may be provided with the mounting yoke 42' in a position to 95 be secured by the bolts 50 holding the outlet fitting 47 upon the side of the cylinder casting, (see Fig. 3) and the terminals of the arms 45', 46'' may then be made concentric with the bolt 50. In such event, in case it 100 becomes desirable to connect the motor up with the regular radiator, it is only necessary to loosen the bolt 50 and the hose couplings 48' and 49' corresponding to the couplings 48 and 49 before mentioned, when the device may be moved pivotally so that its 105 lower arm will swing forwardly and upwardly, clearing the way for the engagement of the usual conduit pipe from the outlet 14 of the motor to the inlet 51 at the 110 lower part of the usual radiator. The coupling 33 may then be removed and the ordinary coupling replaced and hose connections made as ordinarily practised. 110
- What is claimed: 115
1. A device of the character described comprising a motor having a water jacket provided with inlet and outlet, a plurality of resilient brackets carried by the motor, a reservoir mounted thereon, having inlet and outlet, flexible connections between the outlet of the motor and the inlet of said reservoir, a coil element pivotally mounted upon said motor and having terminal portions of different radii extending in a common direction concentric to the pivot of the coil, an outlet and inlet fitting on said reservoir and water jacket of the motor adapted to aline with respective terminals of the coils, and flexible connections between said 120 125 130

5 fittings and respective ends of the coil, the lower arm of said coil being disposed beneath the inlet of the water jacket and having a drain cock thereon.

2. In a device of the character described a bracket mounting for reservoirs of the character described comprising a portion of strap metal having a horizontal part, one end portion being bent closely inward thereunder and extended downwardly there beneath diagonally, the other end of the device being extended downwardly, and both ends constructed for attachment to a support, a tank yoke having screw threaded end por-
- 10

15 tions engaged slidably through the horizontal part of said bracket and said inturned portion closely adjacent the point of bend, and nuts engaged upon the yoke ends at the under part of the bracket, for the purposes described.

20 In testimony whereof we have affixed our signatures in the presence of two witnesses.

FRANK HINDE.
WALTER H. FLEWELL.
